UNITED STATES PATENT OFFICE.

LOUIS LANG, OF NEW YORK, N. Y.

DIAMOND-CUTTER'S DOP.

1,147,517.

Specification of Letters Patent. Patented July 20, 1915.

Application filed October 8, 1914. Serial No. 865,672.

To all whom it may concern:

Be it known that I, LOUIS LANG, a citizen of the United States, and a resident of the city of New York, borough of Manhattan, in the county and State of New York, have invented a new and Improved Diamond-Cutter's Dop, of which the following is a full, clear, and exact description.

This invention relates to a dop to be used by diamond cutters in the cutting and polishing of diamonds, and it has for its general object to overcome the disadvantages in the dops now commonly employed.

More specifically the invention has for its object to provide a novel, simple and effective means for firmly clamping the stone in the dop in such a manner that the table and two facets can be ground without requiring the stone to be unclamped and repositioned.

A further object of the invention is the provision of a novel form of universal joint between the body of the dop and its supporting stem, whereby the dop body is firmly held in any desired position of adjustment while at the same time being readily yieldable when the operator applies pressure to the dop body for effecting the desired adjustment.

With such objects in view, and others which will appear as the description proceeds, the invention comprises various novel features of construction and arrangement of parts which will be set forth with particularity in the following description and claims appended hereto.

In the accompanying drawing, which illustrates one embodiment of the invention and wherein similar characters of reference indicate corresponding parts in all the views, Figure 1 is a side view of the dop, showing the body in full lines in such relation to the stem as to cut the table of a diamond and showing by dotted lines the two opposite angular positions for cutting two diametrically opposite facets; Fig. 2 is an enlarged sectional view on the line 2—2, Fig. 1; Fig. 3 is a view of the upper section of the dop removed, the plane of separation being indicated by the line 3—3, Fig. 2; Fig. 4 is an enlarged sectional view of the adjusting ring for the clamping hooks; and Fig. 5 is a sectional view showing the universal adjustment and clutch features in connection with a lead dop.

Referring to the drawing, A designates

the body of the dop, which is mounted for universal adjustment on a rigid stem B, the universal adjustment being provided for by a ball and socket joint C.

The dop is made preferably, although not necessarily in an upper diamond-holding section a and a lower socket section a', and these two sections are separable on a plane transverse to the stem B, and they may be secured together in any suitable manner, as, for instance, by screws 1, Fig. 2.

The upper section a is approximately frusto-conical and at its top is provided with a tapering socket 2 for receiving a corresponding shaped diamond-holding cup 3 which is removable so that it can be interchanged with cups of other size, according to the dimensions of the diamond to be cut. The under part of the section a is formed with a horizontal circular chamber 4, and a vertical passage or slit 5 extends downwardly through the center of the section A from the top thereof to the chamber 4, the slit or space 5 serving to accommodate the clamping hooks 6 and 6' and their actuating means. These hooks are disposed at opposite sides of the cup 3 and they move inwardly and outwardly in a lateral direction with respect to the cup and also axially thereof. The lower ends of the clamping hooks are provided with longitudinal slots 7 through which extend pivot pins 8 whereby the hooks are movably retained in place. Engaged with and disposed between the hooks 6 and 6' is a U-shaped spring 9 located within the passage 5, and the tension of this spring is such that it tends to force the diamond-engaged hooks 6 and 6' apart. The means for forcing the hooks laterally toward each other and into engagement with the stone and also for drawing the hooks inwardly in an axial direction for clamping the stone in the cup are the wedges 10 and 10' which are employed respectively in connection with the hooks 6 and 6'. These wedges slide on surfaces 12 formed by the sides of the passage 5 and they are connected with means within the section a, whereby the wedges can be forced inwardly or outwardly. The wedge-operating means comprises a disk 13 which is provided with diametrically opposite slots 14 to receive the lower ends of the wedges 10 and 10', and in these slots the wedges are pivotally secured by pins 15 carried by the disk 13. The circumference of the disk

is connected to the eye 20 at the central top portion of the rear part of the plow, this cable passing over suitable pulleys or sheaves 21, 22 and 23 to any suitable windlass or winding device 24.

The rear plows 25 and 26 are provided with suitable skeleton bracings 27 on their inner sides and at their forward and rear lower parts they have idle or caster wheels 28 and 29 which are free to swing like the wheels 8 and 12, and consequently, these wheels 28 and 29 automatically trail according to the direction in which the machine is advancing or turning. An inverted U-shaped guide frame 30 rising from the chassis 1 serves as a guide for the collars 31 which slip up and down thereon and to which the front portions of the plows 25 and 26 are connected by eye-bolts 32, as shown in Figs. 7 and 10. Stout coil springs 33 connect the lower corners of the plows 25 and 26 to brackets 34 on the chassis and the direction of pull of these springs is such that they hold the lower forward corners of the plows 25 and 26 in proper position. The slides 31 and eye-bolts 32 provide means whereby the plows 25 and 26 may be raised or lowered to any desired position, and whatever position they may assume they are adapted to be swung inwardly and outwardly in relation to the chassis 1 and further, the rear ends of the plows 25 and 26 may, by reason of this joint, be raised or lowered so that the general forward extent of each plow may be arranged at any desired inclination to the horizontal. Extending longitudinally of the chassis 1 is a guide bar 35 which is rigidly fastened by the braces 36. Supplemental frames 37, suitably braced, are hinged at 38 to the upper and lower portions of the respective frames 27 and the rear ends of the respective frames 37 have swiveled or eye-bolt joints 39 and a guide or runner 40 which slides on the guide 35. The frames 37 assist in supporting the plows 25 and 26 and also constitute, with the runner 40, means whereby the two frames 27 and the respective plows 25 and 26 carried thereby, may be simultaneously swung inwardly or outwardly to vary the width of the swath cleared by the plows 25 and 26. This adjustment is accomplished by a double cable whose upper and lower stretches 41 and 42 run over a sheave 43, and one of these stretches connects to the runner 40. The cable winds on any suitable windlass 44 located in the same general region as the windlass 24. When the windlass is operated in one direction, the plows 25 and 26 are spread and when operated in the opposite direction, they are drawn toward each other. For the purpose of raising and lowering the collars 31, there are provided independent cables 45 and 46 which run over sheaves 47 and 48 on the

guide frame 30 and are adapted to wind on the respective windlasses 49 and 50 located in the same general region as the windlasses 24 and 44. To raise and lower the rear ends of the plows 25 and 26, I provide cables 51 and 52 connected to the plows 25 and 26, which, after running over pulleys 53 and 54, extend to the respective windlasses 55 and 56 located in the same general region with the windlasses aforesaid. Any suitable winding and locking means may be provided for the windlasses. The form of windlass is not important and other winding means may be provided. While not essential, the braces and frame-work are preferably of angle iron for purposes of lightness and strength and the guide frames 14 and 30 are of tubing.

The front plow may be raised and lowered and held at any desired height and it automatically turns and responds to the direction of movement of the motor vehicle. Each of the rear plows can be independently raised and located at any desired height and tilted to any desired inclination. Both of the rear plows can be simultaneously moved inwardly or outwardly to cut a narrower or wider swath. However the plows may be disposed, the springs 33 hold the wheels 28 and 29 down to run along the surface operated on so that the plows are held to their work. Inward pressure on the plows is resisted by the supplemental frames 37 and the means employed to adjust them.

Having thus described my invention, what I claim as new and desire to secure by Letters Patent, is:

1. In a snow plow, the combination with a vehicle, of a front plow, guides on the vehicle, hinged guide connections thereto from the upper portion of the plow, said plow having loose connections to said guides at points lower down whereby said plow is free to automatically tilt at all times and when at any height and may be raised and lowered independently of said tilting, and means for bodily raising and lowering said plow independently of its adaptability to automatically tilt.

2. In a snow plow, the combination with a vehicle, of a front plow, and guiding and adjusting means adapted to permit up and down movement of the snow plow and tilting movement thereof comprising upright guides on the vehicle, hinge collars on the plow which are slidable on the guides, and forks on the plow which are slidable on the guides.

3. In a snow plow, the combination with a vehicle, of a front plow, guides on the vehicle, hinged guide connections thereto from the upper portion of the plow, said plow having loose connections to said guides at points lower down whereby said plow is

and at the sides, a rotatable ring mounted in the chamber and having its periphery engageable by the thumb and finger to the open sides of the chamber, stone clamping means extending out of the top of the chamber and movable inwardly and outwardly for clamping and unclamping the stone, and a device operatively connected with the ring and with the said means for moving the latter by the rotation of the ring.

2. A diamond cutter's dop comprising a body, an operating ring rotatably mounted therein and confined against axial movement, said ring being internally threaded, a disk threaded in the ring, means for preventing the disk from turning and permitting the disk to move axially, stone-engaging clamping hooks mounted in the body, and means connected with the disk and operatively connected with the clamping hooks for actuating the latter by the movement of the said ring.

3. A diamond cutter's dop comprising a body, an operating ring rotatably mounted therein and confined against axial movement, said ring being internally threaded, a disk threaded in the ring, means for preventing the disk from turning and permitting the disk to move axially, stone-engaging clamping hooks mounted in the body, wedges pivotally connected with the disk and engaging the hooks for moving the same into stone-clamping position as the wedges move in one direction, and spring means for disengaging the hooks as the wedges move in the opposite direction.

4. A diamond cutter's dop comprising a dop body provided with a socket, the body being made in two parts screwed together and separable on a plane passing through the socket, a fixed ball disposed in the socket and on which the body is movable, a resilient lining disposed between the ball and one part of the body and subjected to compression by the screwing of the parts of the body together, an element mounted in the ball and having a spherical surface projecting out of the same, and spring means arranged in the ball and acting on the said element to press the same against the lining.

5. A dop comprising a body, a stone-re-

ceiving cup mounted therein, clamping hooks movably mounted on the body, wedging means for forcing the hooks into engagement with a stone in the cup, and means having a threaded engagement with the wedging means for operating the same.

6. A dop comprising a body, a stone-receiving cup mounted therein, clamping hooks movably mounted on the body, non-rotatable wedging means located within the body for forcing the hooks into engagement with a stone in the cup, means located within the body for operating the wedging means, and means for moving the hooks out of engagement with the stone when the wedging means is released from the hooks.

7. A dop comprising a body, a stone holder therein, a pair of clamps disposed at opposite sides of the holder, a rotatable element mounted within the body and held against axial movement, and means actuated thereby for moving the clamps into engagement with the stone.

8. A dop comprising a body, a stone holder therein, a pair of clamps disposed at opposite sides of the holder, a rotatable element in the body, a non-rotating member having a threaded engagement with the rotatable element; and means connected with the said member for forcing the clamps into engagement with the stone in the holder.

9. A dop comprising a body, a stone holder therein, a pair of clamps disposed at opposite sides of the holder, a rotatable element in the body, a non-rotating member having a threaded engagement with the rotatable element, wedges hingedly connected with the said member and engaging the clamps to force the same in engagement with a stone in the holder, surfaces on which the wedges slide, and means for releasing the clamps when the action on the wedges is removed from the same.

In testimony whereof I have signed my name to this specification in the presence of two subscribing witnesses.
